TOOL

Allen Nathaniel Smith, Patterson, Ga.

Application May 2, 1934, Serial No. 723,596

1 Claim. (Cl. 254—22)

The invention relates to a tool and more especially to a pull tool.

The primary object of the invention is the provision of a tool of this character, wherein a single handle is employed for the operation of the tool, it being especially designed for employment by workmen in applying collecting tins and nails to tree trunks from which turpentine is to be collected, the nails serving to support a cup with relation to the tin, so as to collect the turpentine, yet the said tool is adaptable for use by roof tinners, carpenters or other artificers for pulling tin from roofs, for lifting floor boards, for removing nails from walls, for removing metal laths, etc.

Another object of the invention is the provision of a tool of this character, wherein the single handle assures maximum leverage for pulling purposes and with minimum effort on the part of the operator or user of the tool.

A further object of the invention is the provision of a tool of this character, wherein the uses thereof are diversified and such tool is capable of being handled in a convenient manner and with dispatch, without inconvenience to the user thereof and with assured results for the purposes intended thereof.

A still further object of the invention is the provision of a tool of this character which is simple in construction, thoroughly reliable and efficient in its purposes, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a side elevation of a tool constructed in accordance with the invention.

Figure 2 is a plan view thereof.

Figure 3 is an end elevation.

Similar reference characters indicate corresponding parts throughout the several views in the drawing.

Referring to the drawing in detail, the tool comprises an actuating lever 5, one end portion thereof constituting a handle 6 having a bifurcated nail extracting claw 7 angularly disposed with

respect to said handle, while the other end of this lever constitutes a curved jaw 8.

The lever 5 next to the jaw 8 is swingingly connected with an arcuate-shaped fulcrum member 9, the swinging connection being had through a pivot 10 engaged with the member and said lever. This fulcrum member 9 is formed with the inwardly curved jaw 11, mating with the jaw 8, and the heel end 12 rounded as at 13.

Formed on the outer side of the jaw 11 is a bifurcated nail extracting claw 14. The jaws 8 and 11 carry flat gripping plates 15 and 16, respectively, the latter plate being disposed at substantially right angles to the plate 15 when the jaws 8 and 11 are in closed relation to each other and being formed with a beveled biting edge 17. These plates 15 and 16 are adapted to grip the work to be pulled, while the heel end 12 contacts with a support and is the fulcrum of the tool during the pulling operation thereof upon the work.

It should be apparent that either claw 7 or 14 can be utilized for extracting nails, it being also possible to grip the nail between the plates 15 and 16 for its removal, and in the use of the claws the points 18 and 19, respectively, constitute the fulcrum areas for cooperation therewith.

The fulcrum member 9 has the offset bend 20 to have the jaws 8 and 11 aligned with each other.

It should be apparent that the single handle 6 will enable the tool to be operated and maximum leverage had with a minimum energy on the part of the user of the tool.

What is claimed is:

A tool of the character described comprising an actuating lever, one end portion constituting a handle and the other end of said lever constituting a curved jaw, an arcuate-shaped fulcrum member pivoted to said lever next to the curved jaw, said fulcrum member being formed with an inwardly curved jaw mating with the jaw on the lever, a plate on the curved jaw of the lever, a gripping member on the curved jaw of the fulcrum member and disposed at substantially right angles to the plate, the gripping member being formed with reversely beveled portions to provide a biting edge thereto, the opposite end of the fulcrum member being rounded, and a pivot swingingly connecting the lever and fulcrum member together.
